PLUG-IN SWITCH-CONTROLLED MULTIPLE OUTLET

Ward A. Young, 341 Old Fort Road,
King of Prussia, Pa. 19406

Filed Mar. 11, 1970, Ser. No. 21,852

Term of patent 14 years

Int. Cl. D13—03

U.S. Cl. D26—1

FIG.1.

FIG. 2.

FIG.3.

FIG. 1 is a front perspective view of a plug-in switch-controlled multiple outlet in accordance with the present invention;

FIG. 2 is a view in side elevation of the device shown in FIG. 1; and

FIG. 3 is a rear perspective view of the device.

I claim:

The ornamental design for a plug-in switch-controlled multiple outlet, substantially as shown.
